(57) **CLAIM**

The ornamental design for an accessory mount, as shown and described.

DESCRIPTION

FIG. 1 is a top perspective view of the claimed design; FIG. 2 is a bottom perspective view of the claimed design; FIG. 3 is a front view of the claimed design; FIG. 4 is a back view of the claimed design; FIG. 5 is a right side view of the claimed design; FIG. 6 is a left side view of the claimed design; FIG. 7 is a top view of the claimed design; and, FIG. 8 is a bottom view of the claimed design.

The figures illustrate an accessory mount. The claimed accessory mount is used to mount accessories to a vehicle cupholder, a child's car seat, or a child's stroller. In the drawings, the broken lines depict environmental subject matter only and form no part of the claimed design.
